REPRODUCER ARM ASSEMBLY

Leo J. Aucoin, West Hartford, Conn., assignor to The Gray Manufacturing Company, a corporation of Connecticut

Application September 19, 1957, Serial No. 47,779

Term of patent 14 years

(Cl. D26—14)

Fig. 1 is a perspective view of a reproducer arm assembly, showing my new design;

Fig. 2 is a top plan view; and

Fig. 3 is a perspective view thereof, with the parts in different relative positions.

I claim:

The ornamental design for a reproducer arm assembly, as shown.
